TOP BAR ATTACHMENT DEVICE FOR
FRAMELESS WINDOW SCREENS

David Jordan Rust and Jack H. Jensen, San Leandro, Calif., assignors to Ry-Lock Company, Ltd., San Leandro, Calif., a corporation of California

Application July 21, 1952, Serial No. 300,060

7 Claims. (Cl. 160—327)

1

This invention relates generally to improvements in frameless window screens of the type wherein a section of wire cloth is fitted with a top cross bar and a bottom cross bar; the top cross bar being secured to the header of a window frame by transversely spaced attachment devices, while the bottom cross bar is retained in place—with the screen taut—by suitable tensioning devices.

The present invention is directed in particular to, and it is a major object to provide, an improved top bar attachment device for use in a frameless window screen characterized as above.

Another object of the instant invention is to provide a top bar attachment device which permits of ready securing of the top bar to the header of a window frame, yet allows such top bar and the screen to be easily manually detached for cleaning, repair, replacement, or winter storage.

An additional object of this invention is to provide a top bar attachment device which is secured to such bar in novel manner and so that separation of the parts cannot occur by reason of the relatively great tension to which the screen is subjected when in use.

A further object of the invention is to provide a top bar attachment device which includes a fixed plate and a slide; the latter being secured in guided relation on the fixed plate—for limited longitudinal sliding motion—by a novel structural arrangement.

It is also an object of the invention to provide a top bar attachment device designed for ease and economy of manufacture and installation; the device, other than a headed screw and a rivet, embodying only two parts, both of the latter being capable of mass production, from sheet metal, by means of simplified stamping and die units.

Still another object is to provide a practical, reliable, and durable top bar attachment device for frameless window screens, and one which will be exceedingly effective for the purpose for which it is designed.

These objects are accomplished by means of such structure and relative arrangement of parts as will fully appear by a perusal of the following specification and claims.

In the drawings:

Fig. 1 is an end elevation of one of the devices as in use.

Fig. 2 is a transverse sectional elevation of the same.

Fig. 3 is a bottom plan view of one of the de-

vices as in use, with the slide retracted to permit of engagement of the screw in, or to remove it from, the notch assembly.

Fig. 4 is a similar view, but shows the slide advanced whereby to lock the device on the screw.

Fig. 5 is a perspective exploded view of the device showing the parts immediately prior to their assembly.

Referring now more particularly to the characters of reference on the drawings, the numeral 1 indicates—generally—a frameless or tension type window screen, which screen is fitted with a top cross bar 2. Such top bar 2 has a full width, upstanding attachment flange 3 which lies in abutment against the front of the horizontal blind stop 4 included in the header 5 of a window frame, indicated generally at 6.

The upstanding flange 3 of the top cross bar 2 is supported, and held in engagement with the blind stop 4, by two or more transversely spaced top bar attachment devices secured to the blind stop 4 from the under side; one of said devices being indicated generally at 7.

Each of the top bar attachment devices 7 comprises an elongated rectangular flat top plate 8 adapted to abut against the blind stop 4 from below.

At its forward edge, and intermediate its ends, the top plate 8 is formed with an integral, upstanding attachment ear 9 which has a slight forward offset relative to said edge.

The attachment ear 9 passes through a slot 10 in flange 3, and thence upstands in face-to-face abutment with such flange; the flange 3 and ear 9 being fixedly secured together by a rivet 11 which passes through matching holes in the parts. The hole in the ear 9 is indicated at 12.

An elongated rectangular slide 13 engages against the top plate 8 on the under side of the latter; such slide being supported and guided for limited longitudinal sliding motion by the following structural arrangement:

45 A finger tab 14 depends in integral relation from the rear edge of the top plate 8 at one end portion thereof, and a finger 15 is struck from such tab 14 and bent inwardly, projecting toward the top cross bar 2 in adjacent but spaced relation to the top plate 8. The finger 15 thus lies beneath and supports the slide 13, effectively maintaining it against downward displacement at the related end, but without restricting longitudinal sliding motion.

50 At the opposite end of the top plate 8 the

Fig. 3 is a bottom plan view of one of the de-

55

same is formed with an integral, inverted T-shaped supporting and guide tongue 16. The shank of such tongue projects downwardly through an elongated slot 17 in the slide 13, with the transversely extending T-head of said tongue 16 engaging such slide from below.

With this arrangement the inverted T-shaped tongue 16 not only supports the related portion of the slide, but permits the latter to move longitudinally, yet with limitation of such movement to a predetermined extent.

At the end adjacent the tongue 16 the slide 13 is formed with a downturned finger tab 18 to facilitate manipulation of such slide.

The top plate 8 and the slide 13 are initially assembled by first disposing the parts in the relative positions shown in Fig. 5, wherein said slide is at right angles to the cross plate, with the tongue 16 in alignment with slot 17. Thereafter, the tongue 16 is projected downwardly through said slot 17, and the slide 13 is thence turned 90° until it lies parallel to and below the top plate 8 supported by the finger 15. With the parts in this position, the ear 9 is then attached to the flange 3 in the manner previously described; thus confining the slide 13 between the tab 14 and top cross bar 2. The width of the slide 13 is such that when it is so confined it cannot have any substantial lateral swinging motion, but is not restricted from longitudinal sliding motion.

The top plate 8 and slide 13 have notches 19 and 20, respectively, formed therein intermediate their ends; the notch 19 being straight transversely of the plate 8 and opening to the rear edge thereof in clearance relation to the finger tab 14.

The notch 20 in the slide 13 is L-shaped or of L-shaped or bayonet type, and opens to the rear edge of the slide 13 intermediate its end.

With the illustrated arrangement, the inner portions of both notches 19 and 20 always remain in register, whether the slide be retracted, as in Fig. 3, or advanced, as in Fig. 4. When the slide 13 is retracted, as in Fig. 3, the outer portions of the notches 19 and 20 likewise register to permit of the engagement of each device 7 on a headed screw 21 which is threaded into, and depends a short distance below, the blind stop 4. The finger tab 14 is used to manipulate each device 7 to so engage the same on the related headed screw 21.

After the screw 21 is engaged in the registering inner portions of the notches 19 and 20, and at which time the flange 3 is in face-to-face abutment with the blind stop 4, the slide 13 is shifted from its retracted position of Fig. 3 to the advanced position of Fig. 4. In such advanced position of the slide, the notch 20—by reason of its bayonet type—closes with respect to the notch 19, thereby effectively preventing relative escape of the screw 21 from the device.

Shifting of the slide 13 to and fro—i. e. between its retracted and advanced positions—is facilitated by the provision of the down-turned finger tab 18 disposed for ready manual access.

With the described top bar attachment device, a frameless or tension type window screen can be readily and conveniently attached to, or detached from, the blind stop 4 of a window frame header 5; this being accomplished simply by appropriate manipulation of the slide 13 whereby to lock the screw 21 in, or to release it from, the notch assembly.

From the foregoing description it will be readi-

ly seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

10 Having thus described the invention, the following is claimed as new and useful, and upon which Letters Patent are desired:

1. A top cross bar attachment device, for a frameless window screen having a top bar engaging the front of the horizontal blind stop of a window frame header; comprising a horizontal top plate extending lengthwise of the top bar in abutment with the blind stop from below, means securing the top plate to the top bar, a horizontal

15 slide engaging the top plate from below, means to support the slide from the top plate for limited guided horizontal sliding motion parallel to said top plate, the top plate and slide having notches therein open to their rear edges, inner portions 20 of said notches being in register at all times, and a headed screw extending through said registering inner portions of the notches into the blind stop; the inner portion of the notch in the slide being elongated lengthwise of the slide to facilitate said motion thereof, and the outer portions 25 of said notches registering only in a predetermined position of the slide.

2. A top cross bar attachment device, for a frameless window screen having a top bar engaging the front of the horizontal blind stop of a window frame header; comprising a horizontal top plate extending lengthwise of the top bar in abutment with the blind stop from below, the top bar having a slot therethrough in front

30 of the top plate, a forwardly offset upstanding attachment ear on the front edge of the top plate, said ear extending through the slot in the top bar and thence abutting the front face of the latter, means securing the ear to said top bar, a horizontal slide engaging the top plate from below, means to support the slide from the top plate for limited guided horizontal sliding motion parallel to said top plate, the top plate and slide having notches therein open to their rear edges, inner portions 35 of said notches being in register at all times, and a headed screw extending through said registering inner portions of the notches into the blind stop; the inner portion of the notch in the slide being elongated lengthwise of the slide to facilitate said motion thereof, and the outer portions of said notches registering only in a predetermined position of the slide.

3. A top cross bar attachment device, for a frameless window screen having a top bar engaging the front of the horizontal blind stop of a window frame header; comprising a horizontal top plate extending lengthwise of the top bar in abutment with the blind stop from below, means securing the top plate to the top bar, a horizontal slide engaging the top plate from below, means to support the slide from the top plate, said last named means providing limited guided horizontal sliding motion parallel to said top bar, said last named means including a longitudinal slot in the slide and an inverted T-shaped tongue projecting from said plate through the slot with the T-head below said slide, the top plate and slide having notches

40 lengthwise of the slide to facilitate said motion thereof, and the outer portions of said notches registering only in a predetermined position of the slide.

4. A top cross bar attachment device, for a frameless window screen having a top bar engaging the front of the horizontal blind stop of a window frame header; comprising a horizontal top plate extending lengthwise of the top bar in abutment with the blind stop from below, means securing the top plate to the top bar, a horizontal slide engaging the top plate from below, means to support the slide from the top plate, said last named means providing limited guided horizontal sliding motion parallel to said top bar, said last named means including a longitudinal slot in the slide and an inverted T-shaped tongue projecting from said plate through the slot with the T-head below said slide, the top plate and slide having notches

45 lengthwise of the slide to facilitate said motion thereof, and the outer portions of said notches registering only in a predetermined position of the slide.

5. A top cross bar attachment device, for a frameless window screen having a top bar engaging the front of the horizontal blind stop of a window frame header; comprising a horizontal top plate extending lengthwise of the top bar in abutment with the blind stop from below, means securing the top plate to the top bar, a horizontal slide engaging the top plate from below, means to support the slide from the top plate, said last named means providing limited guided horizontal sliding motion parallel to said top bar, said last named means including a longitudinal slot in the slide and an inverted T-shaped tongue projecting from said plate through the slot with the T-head below said slide, the top plate and slide having notches

50 lengthwise of the slide to facilitate said motion thereof, and the outer portions of said notches registering only in a predetermined position of the slide.

of said notches being in register at all times, and a headed screw extending through said registering inner portions of the notches into the blind stop; the inner portion of the notch in the slide being elongated lengthwise of the slide to facilitate said motion thereof, and the outer portions of said notches registering only in a predetermined position of the slide.

4. A top cross bar attachment device, as in claim 3, in which the top plate is formed with an integral finger tab depending from its rear edge; and said slide supporting means includes a finger struck from the tab and bent inwardly below the slide; the finger being spaced from said T-shaped tongue and on the opposite side of the 15 registering portions of said notches.

5. A top cross bar attachment device, for a frameless window screen having a top bar engaging the front of the horizontal blind stop of a window frame header; comprising a horizontal 20 top plate extending lengthwise of the top bar in abutment with the blind stop from below, means securing the top plate to the top bar, a horizontal slide engaging the top plate from below, a finger tab integral with and depending from the rear edge of one end portion of the top plate, a finger struck from said tab and in-turned beneath the slide in supporting relation thereto, a longitudinal elongated slot through 25 the opposite end portion of the slide, an inverted T-shaped tongue integral with and depending from the adjacent end of the top plate, the tongue projecting through the slot with the T-head below and supporting the slide, a finger tab depending from one end of the slide, the 30 top plate and slide having notches therein open to their rear edges intermediate their ends, inner portions of said notches being in register at all times, and a headed screw extending through said registering inner portions of the 35 notches into the blind stop; the inner portion of the notch in the slide being elongated lengthwise of the slide to facilitate said motion thereof, and the outer portions of said notches registering only in a predetermined position of the slide.

6. A top cross bar attachment device, as in claim 5, in which the slide is of a width, front to rear only slightly less than the distance from the first named finger tab to the top bar.

7. A top cross bar attachment device, for a frameless window screen having a top bar engaging the front of the horizontal blind stop of a window frame header; comprising a horizontal top plate extending lengthwise of the top bar in abutment with the blind stop from below, a horizontal slide engaging the top plate from below, the top bar having a slot therethrough in front of the top plate, a forwardly offset up-standing attachment ear on the front edge of the top plate, said ear extending through the slot in the top bar and thence abutting the front face of the latter, means securing the ear to said stop bar, a finger tab integral with and depending from the rear edge of one end portion of the top plate, a finger struck from said tab and in-turned beneath the slide in supporting relation thereto, a longitudinal elongated slot through the opposite end portion of the slide, an inverted T-shaped tongue integral with and depending from the adjacent end of the top plate, the tongue projecting through the slot with the T-head below and supporting the slide, a finger tab depending from one end of the slide, the top plate and slide having notches therein open to their rear edges intermediate the ends, inner portions of said notches being in register at all times, and a headed screw extending through said registering inner portions of the notches into the blind stop; the inner portion of the notch in the slide being elongated lengthwise of the slide to facilitate said motion thereof, and the outer portions of said notches registering only in a predetermined position of the slide.
